UNITED STATES PATENT OFFICE.

ALBERT BREAKENRIDGE KNIGHT, OF FAIRMONT, WEST VIRGINIA.

MACHINE FOR BURNING OR GLAZING THE EDGES AND SIDES OF GLASSWARE.

1,364,939.

Specification of Letters Patent. Patented Jan. 11, 1921.

Application filed August 8, 1919. Serial No. 316,102.

To all whom it may concern:

Be it known that I, ALBERT B. KNIGHT, a citizen of the United States, residing at Fairmont, in the county of Marion and 5 State of West Virginia, have invented certain new and useful Improvements in Machines for Burning or Glazing the Edges and Sides of Glassware, of which the following is a specification.

This invention relates to new and useful improvements in machines for burning or glazing the edges and sides of glassware.

An important object of the invention is to provide means for simultaneously glazing 15 the edges and sides of tumblers.

A further important object is to eliminate the objectionable features present in this form of machine.

As at present constructed, machines of 20 this type are provided with a number of spindles adapted to receive the tumblers in cups carried upon their upper ends. These spindles are raised and lowered by means of a plate contacting the lower ends thereof. 25 I have found that the spindles in practice, are easily bent and must, therefore, be replaced. It will be understood that in a machine of this type, these spindles must necessarily be of some length as the machine 30 must be used for glazing very short tumblers as well as the long stemmed type to be of any practical value.

In my construction, instead of raising or lowering the spindles themselves, I have 35 provided a carrier for the spindles which may be raised or lowered, thereby removing the thrust from the lower end of the spindle.

Other objects and advantages of my invention will be apparent during the course 40 of the following description.

In the accompanying drawings forming a part of this specification and in which like numerals are employed to designate like parts throughout the same,

45 Figure 1 is a side elevation of my machine,

Fig. 2 is a section taken on line 2—2 of Fig. 1,

Fig. 3 is a section taken on line 3—3 of 50 Fig. 2,

Fig. 4 is a section taken on line 4—4 of Fig. 1,

Fig. 5 is a section taken on line 5—5 of Fig. 1,

55 Fig. 6 is a section taken on line 6—6 of Fig. 1,

Fig. 7 is a section taken on line 7—7 of Fig. 1,

Fig. 8 is a plan view of the drive for the machine,

Fig. 9 is a front elevation of the burner, and,

Fig. 10 is a section taken on line 10—10 of Fig. 4.

Referring now more particularly to the drawings, the numeral 10 indicates a suitable base upon which is mounted a socket flange 11, having a socket 12 formed therein.

Seated in the socket 12 is a vertical shaft 13, which is held against rotation by a set 70 screw 14 or the like. Seated upon the upper end of the socket flange 11 is a thrust bearing 15, upon which is mounted a sleeve 16, surrounding the shaft. The sleeve 16 is provided upon its lower end with an out- 75 standing flange 17, to which is secured, by means of bolts or the like, a sprocket gear 18. Secured to the base 10 is a support 19, to the outer end of which is secured a vertical member 20 having upper and lower 80 brackets 21 and 22 secured thereto. Rotatably mounted in journals formed in these brackets is a vertical shaft 23, provided upon its upper end with an operating handle 24. Adjacent its lower end, the shaft 23 is pro- 85 vided with a sprocket gear 25, alined with the sprocket gear 18 and connected thereto with a chain 26. It will be readily seen that when the handle 24 is rotated, the sleeve 16 is rotated simultaneously therewith. 90

The sleeve 16 is provided upon its upper end with external screw-threads 28. Mounted upon the upper end of the sleeve 16 is an internally threaded sleeve 27, the internal threads of which engage with the 95 external threads 28 of the sleeve 16. The upper end of the sleeve 27 has an inturned flange 29, having a central aperture adapted to receive the vertical shaft 13. Mounted upon the flange 29 is a thrust bearing 30, 100 or its equivalent, upon which is in turn mounted a hub 31, having radial arms 32, which distend a gear 33.

Secured upon the base 10 is a standard 34 embodying journals 35 and 36. Mounted 105 in these journals is a vertical tubular member 37 to which is secured a gear 38. This gear, in the present instance, is shown as comprising a worm gear which meshes with a worm 39, formed upon the shaft of a 110 motor 40. The tubular member 37 is provided with a vertical slot 41, and provides

at its upper end a bushing 42, forming a journal to receive a shaft 43. The lower end of the shaft 43 has an enlarged portion 44, having a sliding fit with the interior of the tubular member 37 and is provided upon this enlargement with a pin 45 engaging in the vertical slot 41. Adjacent its upper end, the shaft 43 is provided with spaced flanges 46 and 47. Secured to the sleeve 27 is a bracket 48, provided with an extension 49, adapted to receive the shaft 43 between the flanges 46 and 47. The shaft 43 is provided upon its upper end with a pinion 50, meshing with the gear 33.

15 A bracket 48 is secured to the sleeve 27 and this bracket is provided with a plate 49, having an opening therein for the reception of the sleeve 43, the plate 49 being adapted to be arranged between the flanges 46 and 47.

20 It will be readily seen that the bracket 48 and its extension 49, engaging the shaft 43, perform a two-fold purpose, the shaft 43, being incapable of transverse movement, prevents rotation of the sleeve 27 and the sleeve 27, and its bracket when raised or lowered by the rotation of the sleeve 16, will move the shaft 43 correspondingly. As the hub of the gear 33 rests upon the upper end 25 of the sleeve 27, it will be readily seen that the pinion 50 is kept in permanent engagement with the gear 33 and rotation of the sleeve 37 transmitted to the gear 33 by means of pin 45, shaft 43 and pinion 50.

25 Secured to the upper face of the gear 33 by means of bolts 51 or the like, are a plurality of radial arms 52. These arms are provided upon their outer ends with substantially C-shaped frames 53, providing spaced journals 55, affording a support for the bottom of the spindle. Secured upon the spindle 56 intermediate the journals 54 and 55 is a pinion 57, the purpose of which will hereinafter appear.

30 45 Mounted upon the upper end of the hub 31 of gear 33 is a hub 58, rotation of the hub 58 being prevented by means of screws 59, or the like, engaging in key-ways 60, formed in the shaft 13. The hub 58 is provided with radial arms 61, distending a gear 62, meshing with the pinions 57 secured to the spindles 56.

35 55 At spaced intervals, as for example, at intervals of ninety degrees, I prefer to provide rollers 63, secured to the spindle journals 54. These rollers rest upon the upper face of the gear 62, and have a tendency to relieve the torque upon the gear 33, placing a portion of the weight upon the gear 62. The spindles 56 are provided upon their upper ends with the usual sockets 64, adapted to receive the base of the tumbler to be glazed.

40 Secured to the upper end of the shaft 13 by means of a flanged bracket 65 is a support 66. Secured to the support 66 in any

desired manner is a burner member 67, comprising a semi-circular casing 68 provided upon its periphery with rows of openings 69 and 70. By referring to Fig. 9, it will be seen that the openings 69 are in a straight line parallel with the base of the machine and that the openings 70 are arranged upon a curved line. The casing 68 is connected by means of conduits 71 with a suitable source of combustible fuel supply 72. Secured upon the upper peripheral edge of the casing 68 is a receptacle 73 having a filler 74 composed of refractory material, such as fire clay. It will be seen by examining Fig. 2, that the openings 69 direct a jet of flame against the fire clay and the heat of the flame is reflected downwardly upon the edge of the tumbler. The fire clay is formed tapered outwardly so that the hottest portion of the flame is spaced as far as feasible from the upper edges of the tumbler and the outer edge of the flame is brought as close as feasible to the tumbler. The purpose of this tapered construction is to apply to the upper edge of the glassware a uniform heat.

45 The operation of my device is as follows: The tumblers are placed in the sockets 64 of the spindles 56 and raised or lowered by rotating the handle 24 until the tumblers are in the proper spaced relation with the fire clay 74. The burner 67 is then ignited and the motor started. The arms 52 being fixed upon the gear 33 are rotated therewith and as the gear 62 is fixed against rotation, the spindles 56 are rotated through the medium of the pinion 57 meshing with the gear 62. It will be seen that the tumblers are simultaneously advanced and rotated. As the tumblers pass beneath the fire clay 74, the upper edges thereof are glazed by the flame directed from the openings 69. The sides of the tumblers are simultaneously glazed by the staggered openings 70 and by reason of the peculiar construction of this row of openings, flame is directed to all parts 50 of the outside of the tumbler.

55 It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, I claim:

1. In a device of the type described, a fixed shaft, a gear rotatably mounted thereon, means for vertically reciprocating said gear, comprising a sleeve rotatably mounted upon said shaft, and provided with external threads, means for rotating said sleeve, a second sleeve having threaded engagement with said first named sleeve, said second sleeve forming a support for said gear,

means for rotating said gear comprising a driven shaft, a pinion secured thereto and meshing with said gear, and identical means for holding said pinion in engagement with 5 said gear and preventing the rotation of said second sleeve.

2. In a device of the type described, a fixed shaft, a gear rotatably mounted thereon, a plurality of radial arms carried by said 10 gear, spindles rotatably mounted upon said radial arms, means for vertically adjusting said gear comprising, a sleeve rotatably mounted upon said shaft and provided with external threads, means for rotating said 15 sleeve, a second sleeve having threaded engagement with said first named sleeve, said second sleeve forming a support for said gear, means for rotating said gear comprising a tubular member provided with a longitudinal slot, means for rotating said tubular member, a shaft vertically reciprocable 20 within said tubular member, means for preventing rotation of said shaft with relation to said tubular member, a pinion carried by said shaft and meshing with said gear, and means for preventing rotation of said second sleeve.

3. In a device of the type described, a fixed shaft, a gear rotatably mounted thereon, a plurality of radial arms carried by said gear, spindles rotatably mounted upon said radial arms, means for vertically adjusting said gear comprising, a sleeve rotatably mounted upon said shaft and provided with 35 external threads, means for rotating said sleeve, a second sleeve having threaded engagement with said first named sleeve, said second sleeve forming a support for said gear, means for rotating said gear comprising a tubular member provided with a longitudinal slot, means for rotating said tubular member, a shaft vertically reciprocable 40 within said tubular member, means for preventing rotation of said shaft with relation to

said tubular member, a pinion carried by 45 said shaft, and identical means for holding said pinion in engagement with said gear and preventing rotation of said second sleeve.

4. In a device of the type described, a rotatable gear, a second gear coaxial therewith fixed against rotation, means for simultaneously vertically adjusting said gears, spindle journals secured to one of said gears, spindles mounted in said journals and pinions on said spindles meshing with the other 50 55 of said gears.

5. In a device of the type described a rotatable gear, a second gear coaxial therewith fixed against rotation, means for simultaneously vertically adjusting said gears, spindle journals secured to said rotatable gear, spindles mounted in said journals and pinions on said spindles meshing with the gear 60 fixed against rotation.

6. In a device of the type described, a pair of coaxial gears, spindle journals secured to one of said gears, spindles mounted in said journals, pinions on said spindles meshing with the other of said gears, means for rotating one of said gears and means 70 for simultaneously adjusting said gears.

7. In a device of the type described, a rotatable gear, a gear fixed against rotation mounted above said rotatable gear coaxial therewith, means for simultaneously vertically adjusting said gears, spindle journals secured to said rotatable gear, rotatable spindles mounted in said journals, pinions on said spindles meshing with the gear fixed 75 80 against rotation, and rollers rotatably carried by said spindle journals and engaging the upper surface of said last named gear.

In testimony whereof I affix my signature in presence of two witnesses.

ALBERT BREAKENRIDGE KNIGHT.
